Patented Aug. 20, 1918.

UNITED STATES PATENT OFFICE.

GEORGE E. H. NELSON, OF RACINE, WISCONSIN.

TOY.

1,276,561.

Specification of Letters Patent.

Patented Aug. 20, 1918.

Application filed October 31, 1917. Serial No. 199,485.

To all whom it may concern:

Be it known that I, GEORGE E. H. NELSON, a citizen of the United States, residing at Racine, in the county of Racine and State 5 of Wisconsin, have invented certain new and useful Improvements in Toys; and I do hereby declare the following to be a full, clear, and exact description of the invention, such as will enable others skilled in the art 10 to which it appertains to make and use the same.

This invention relates to a new and useful toy or novelty and has for its main object to provide one embodying an upright frame 15 in the form of a ladder having alternately arranged stops on its sides, and a figure having outstretched arms which may be a representation of any well known public or popular character, said figure when positioned at the top of the frame being adapted when started to descend by gravity, alternately swinging from side to side in its descent.

A further object of the invention is to 25 provide a simple and inexpensive toy and one which will afford a great deal of amusement.

With these and other objects in view as will appear as the description proceeds, the 30 invention comprises the various novel features of construction, combination and arrangement of parts as will be fully described hereinafter and afterward specifically claimed.

Referring to the drawings:

Figure 1 represents a front elevation of the toy, showing a figure supported at the top thereof,

Fig. 2 is a similar view showing the manner in which the figure descends, and

Fig. 3 is a side elevation of the upright frame of the toy.

Similar characters of reference are used to denote corresponding parts throughout 5 the accompanying drawings and the following description.

In order that the construction and operation of the invention may be readily understood, I have illustrated an approved embodiment thereof in the accompanying drawings and will now proceed to fully describe the same in connection with said drawings, in which 1 indicates an upright frame, which in this instance is in the form of a ladder and embodies the usual side bars 2 connected by rungs 3. The ladder

is adapted to be supported in an upright position by a pair of legs 4 pivotally connected at their upper ends to the side bars of the ladder as indicated at 5.

Each side bar is provided longitudinally with spaced stop pins 6, the stop pins on one side bar being arranged alternately with the spaces between the stop pins on the opposite side bar.

One side bar has a supporting pin 7 arranged on it opposite the uppermost stop pin on the opposite side bar and is disposed in horizontal alignment therewith.

8 indicates a gravity descending figure 70 which may be made or designed to indicate any well known public or popular character and is provided with outstretched arms 9 extending oppositely in horizontal alignment.

Referring to Fig. 1, it will be seen that the supporting pin 7 coöperates with the uppermost stop pin 6 to support the figure at the top of the ladder by its outstretched arms. In the operation of the toy, the left 80 hand arm is moved outwardly and disengaged from the supporting pin 7 and then allowed to drop, whereupon the arm will fall upon the stop pin 6 immediately below the supporting pin 7. The figure will then 85 slide downwardly by gravity in the position indicated by dotted lines until the outer end of the right arm of the figure disengages the uppermost stop pin 6 which is opposite the supporting pin 7.

As soon as the right arm of the figure has disengaged the uppermost stop pin 6 and the body of the figure engages the next lower stop pin, it will swing downwardly upon the next lower stop pin 6, as clearly 95 indicated in Fig. 2. When the figure is swung down to the dotted line position indicated in Fig. 2, it will slide downwardly on the stop pins until the end of the left arm of the figure leaves the uppermost stop 100 pin supporting it and the body of the figure engages the next lower stop pin, whereupon the figure will alternately swing on this latter stop pin and continue its downward gravity descent.

From the foregoing description taken in connection with the drawings, it will be apparent that when the figure is once started downwardly from the top of the ladder, it will continue to descend until it reaches the 110 bottom of the ladder, alternately swinging from side to side in its descent.

Having thus described my invention, what I claim as new, is:—

A toy consisting of a ladder, legs pivoted to the sides of the ladder to support it in an upright position, stops arranged longitudinally to each side of the ladder, the stops on one side being alternately opposite the spaces between the stops on the opposite side of the ladder, a figure having outstretched arms for alternate engagement with said stops whereby it will swing alternately from side to side of the ladder in its gravity descent, and a supporting pin

mounted on one side of the ladder in transverse alinement with the uppermost stop 15 and adapted to coöperate with the latter to support the figures in elevated position by its outstretched arms.

In testimony whereof I have signed my name to this specification in the presence of 20 two subscribing witnesses.

GEORGE E. H. NELSON.

Witnesses:

FRANK W. DAVIS,
JOHN P. ANDERSON.
